UNITED STATES PATENT OFFICE.

MORRIS ROSEN, OF NEW YORK, N. Y.

DESIGN FOR A TORCHÈRE.

Application filed December 20, 1927. Serial No. 24,558. Term of patent 3½ years.

To all whom it may concern:

Be it known that I, MORRIS ROSEN, a citizen of the United States, residing in New York, in the county of New York and the State of New York, have invented a new, original, and ornamental Design for a Torchère, of which the following is a specification, references being had to the accompanying drawing, forming a part thereof.

The figure is a front view of the torchère showing my new design.

I claim:

The ornamental design for a torchère as shown.

MORRIS ROSEN.
